UNITED STATES PATENT OFFICE.

CHESSBOROUGH JAMES HENRY MACKENZIE-KENNEDY, OF WESTMINSTER, LONDON,
ENGLAND.

AEROPLANE.

1,411,115.

Specification of Letters Patent. Patented Mar. 28, 1922.

Application filed September 8, 1919. Serial No. 322,400.

To all whom it may concern:

Be it known that I, CHESSBOROUGH JAMES HENRY MACKENZIE-KENNEDY, a subject of the King of Great Britain and Ireland, residing at Westminster, London, England, have invented Improvements in or Relating to Aeroplanes, of which the following is a specification.

Aeroplanes have heretofore been provided near to but in front of the tail with guns but these have been "fixed position" guns, that is to say, they have been so mounted as to point directly aft through the tail while the gunner has been accommodated well up in the body of the machine. Consequently there has been little or no angle of fire in a backward direction.

Now according to the present invention an aeroplane is provided behind the tail thereof with a tail gun and accommodation for a gunner.

In carrying out the invention, the body of the machine is provided, aft of the tail, with a hollow built up tail end extension of the necessary body depth to accommodate a gunner and of such lateral and rearward dimensions as seen in plan as to admit of a gun mounting, for instance a "Scarff-ring" or other appropriate gun mounting, for all round fire, being carried by it. Such a gun mounting, provided with a gun swivel and an overhanging gun carrying arm, is or may be so secured to the upper end portion of the hollow tail end extension that the gun carrying arm can be moved into a depressed position in which it will overhang either side, or the extreme tail end of the extension, either in an inclined or vertical position, so as in the latter case to admit of vertical downward fire and the arrangement is such that the gunner has an almost unobstructed view in all directions and so that he can direct and fire his gun through a large horizontal angle laterally and rearwardly and also forwardly, and also, it may be, in an inclined or vertical downward direction, as well as in an upward direction.

Aeroplanes provided with accommodation aft of their tails for tail guns and gunners may also have in the upper parts of the bodies between the main planes and the tail accommodation for guns and gunners, the arrangement of the latter guns being such as

to permit of vertical or oblique fire downwards and upwards. 55

In a machine constructed with a tail end extension for a tail gun as described, the body of the machine may be extended in front of the main wings or planes to a greater extent than the usual proportionate amount, in order that the extra weight thus provided ahead of the centre of gravity of the machine, can be used to partly balance the weight of the said extension and the gun and gunner carried thereby, the complete balance being provided for by other means, as for instance by arranging the engine at an appropriate distance ahead of the centre of gravity. Such an arrangement would ordinarily give an excessive amount of side surface, usually termed "lateral fin area" in front of the centre of gravity of the machine. This however is balanced or counteracted by the considerable depth necessarily given to the tail end extension of the body to accommodate the gunner. In this way any disadvantage that might otherwise arise as the result of providing the machine with a tail gun as described is avoided. 70 75

In order that the tail gun may be directed and fired in a forward and upwardly inclined direction, over the body of the machine without interference from the tail plane, or damage of such tail plane, the machine instead of being provided with a biplane tail, such as is commonly fitted to relatively large armed machines in which the top plane passes as a single unit across and above the tail end of the body and which with its system of cross bracings would thereby almost completely obstruct all forward vision and upwardly inclined vision in a forward direction, of the gunner, there is preferably employed a tail surface of monoplane type consisting of two separate or independent right and left hand tail parts of surfaces each braced as a single complete unit, so as to leave a clear space between the two tail parts or surfaces above the central portion of the body of the machine. The plane of each tail part 100 or surface may advantageously be approximately on a level with the gun when the same is in a position for firing forward and nearly horizontal. Tail planes suitable for the purpose set forth and provided with vertical rudders and fixed fins, can be variously con-

structed but may advantageously be of the construction described in the specification of another application for Letters Patent filed by me and another Serial No. 341,266, filed 5 Nov. 28, 1919. Although it is preferred to use a tail of the monoplane type above referred to, an aeroplane provided with a tail gun as described may be provided with any type of tail plane whether multiplane, bi-plane or monoplane, the essential feature of the invention being the provision of an aeroplane with a tail gun.

The accompanying drawings illustrate one construction of aeroplane embodying the invention, Fig. 1 being a side elevation of the aeroplane, Fig. 2 a longitudinal section with the tail surface removed, Fig. 3 a plan of the tail portion of the body with the outer covering removed, Fig. 4 an elevation of the tail from behind. Fig. 5 is a plan view showing the gun positions behind the main planes.

As will be seen from Fig. 1 the body of the aeroplane is extended aft of the tail *a* where 5 it is constructed to accommodate a gunner and gun mounting for all round fire, whilst, to balance the weights thus added, the body of the machine is also extended in front of the main wings or planes *b* and the engine 10 arranged at an appropriate distance ahead of the centre of gravity. The hollow tail end extension of the body of the machine is formed by extending lateral longitudinal members *c* of the framework of the body, 15 which are connected by transverse frames *d*, sufficiently to the rear of the tail plane to form the required rearward extension; connecting them behind the tail plane and at the rear ends, by outwardly curved or convex 20 upper, lower and intermediate horizontal end members *g*, *h* and *i*, connecting the latter members by one or more outwardly convex 25 vertical members *k*, and covering the open framework thus constituted by wood or 30 other sheathing. Upon the upper outwardly curved or convex member *g* connecting the rear ends of the upper lateral longitudinal members *c* and a transverse member *l* connecting the same longitudinal members at 35 more forward portions of their length, is secured a horizontal gun ring *m* for the tail gun. To the lower portion of the framework 40 of the tail end extension is secured means, such as wood battens *n* to support a floor 45 for the said extension within which is or may be a support *o* adapted to form a kneeling pad or a seat for the gunner, according 50 as he is firing rearwardly or forwardly, the head or head and shoulders of the gunner 55 extending upward through the gun ring *m*. This gun ring may be arranged in a horizontal plane at a lower level than the top of the adjacent portion of the body of the machine.

5 The tail end extension may be provided

with more than one gun, for instance with two guns arranged with their axes parallel to one another.

The tail, shown, comprises two separate parts or surfaces marked *a*, *a'*. Each of the parts is braced independently as a separate unit and supported by inclined struts *p* attached to the body. It will be seen from Fig. 4 that this arrangement is devoid of the usual fins, rudder, struts, framework or 70 bracing above the body where they seriously obstruct the field of fire. Each tail part is provided with a vertical rudder *a*, fixed fin 75 *a'* and elevator *a*.

q, *q*, Figs. 1 and 5, are two gun positions in the upper part of the body of the machine arranged side by side just behind the main planes. These gun positions are arranged close to or overhanging the sides so as to permit of vertical or oblique fire both upwards and downwards over the side. In some cases, there may be more than two gun positions and in other cases only one gun position between the main planes and the tail.

90 What I claim is:

1. An aeroplane provided aft of the tail thereof with a hollow built up tail end extension and one or more guns and accommodation for one or more gunners within 95 said extension substantially as described.

2. An aeroplane according to claim 1 wherein accommodation is also provided in the upper part of the body between the main planes and the tail for one or more guns and 100 gunners, substantially as described.

3. An aeroplane according to claim 1 having a tail comprising two separate parts each suitably supported and braced as a separate unit so as to leave a comparatively clear 105 space above the body for forward fire, substantially as described.

4. An aeroplane according to claim 3 wherein each tail part consists of the usual main and elevator surfaces and is provided 110 at some distance from its body end with one or more vertical rudders and fin surfaces and is supported from the under side by inclined struts, substantially as described.

5. An aeroplane provided aft of the tail 115 thereof with one or more guns and accommodation for one or more gunners and having a tail comprising two separate parts each suitably supported and braced as a separate unit so as to leave a comparatively clear 120 space above the body for forward fire.

6. An aeroplane provided aft of the tail thereof with one or more guns and accommodation for one or more gunners and having gun mountings on opposite sides thereof 125 in rear of and close to the main planes and guns on said mountings arranged to overhang the sides of the body of the machine so as to permit of vertical or oblique fire both upwards and downwards over said sides.

7. An aeroplane provided aft of the tail thereof with a hollow built up tail end extension and one or more guns and accommodation for one or more gunners within said extension, and having a tail surface of monoplane type consisting of two separate or independent right and left hand tail parts or surfaces each braced as a single complete unit, so as to leave a clear space between the two tail parts or surfaces above the central portion of the body of the machine.
- Signed at London, England, this 7th day of July, 1919.

CHESSEBOROUGH JAMES HENRY
MACKENZIE-KENNEDY.
